DISPENSING STOPPER FOR BOTTLES

August L. Voight, Berea, Ohio

Application November 21, 1951, Serial No. 17,484

Term of patent 3½ years

(Cl. D58—26)

To all whom it may concern:

Be it known that I, August L. Voight, a citizen of the United States, residing at Berea, State of Ohio, have invented a new, original, and ornamental Design for Dispensing Stopper for Bottles, of which the following is a specification, reference being had to the accompanying drawing, forming a part thereof, in which

Fig. 1 is a side elevational view of a dispensing stopper for bottles, embodying my new design.

Fig. 2 is a top plan view thereof.

Fig. 3 is a bottom plan view thereof, and

Fig. 4 is a front elevational view thereof.

I claim:

The ornamental design for a dispensing stopper for bottles, as shown.

AUGUST L. VOIGHT.
